Patented Aug. 17, 1920.

UNITED STATES PATENT OFFICE.

RIMMON J. CARR, OF PETOSKEY, MICHIGAN.

CROSSTIE.

1,349,814.

Specification of Letters Patent. Patented Aug. 17, 1920.

Application filed September 29, 1919. Serial No. 327,054.

To all whom it may concern:

Be it known that I, RIMMON J. CARR, a citizen of the United States, residing at Petoskey, in the county of Emmet and State 5 of Michigan, have invented a new and useful Crosstie, of which the following is a specification.

My invention relates to new and useful improvements in cross ties, an important object of the invention being to provide a device which will effectively prevent longitudinal and transverse movement of rails upon the tie and generally improve the construction of the structure disclosed in my 15 Patent No. 905,285.

Another object of my invention is to provide a device which will obviate the necessity of using the ordinary fish-plate and bolts in joining rails, and one which is strong, 20 durable and efficient in practice.

With the above and other objects in view which will appear as the description proceeds, the invention resides in the combination and arrangement of parts and in the 25 details of construction hereinafter described and claimed, it being understood that within the scope of what is claimed, changes in the precise embodiment of the invention shown can be made without departing from the 30 spirit of the invention.

In the accompanying drawings, forming a part of the description and wherein like numerals are employed to designate like parts throughout the same,

35 Figure 1 is a plan view of the invention with the rails applied thereto, the dotted lines showing the position of the various parts when the rails are removed;

Fig. 2 is an end view of the invention;

40 Fig. 3 is a longitudinal section taken on line 3—3 of Fig. 1;

Fig. 4 is a transverse section taken on the line 4—4 of Fig. 1.

Fig. 5 is a perspective view showing the 45 base plate.

In the drawings wherein for the purpose of illustration is shown the preferred embodiment of my invention the numeral 6, designates a cross tie, U-shaped in cross section, in the present instance and similar to the cross tie disclosed in my Patent No. 905,285. Secured to the bottom of the tie, adjacent each end thereof, is a relatively wide supporting plate 7, having a pair of 50 opposite ends extended a substantial distance beyond the longitudinal sides of the

tie whereby the latter is prevented from settling in the foundation upon which it is placed. A rectangular support 8 is secured within the U-shaped tie by means of transverse bolts 9, above each plate 7, and one of these supports is also secured intermediate the ends of the tie. To form a brace for each support 8, a transversely extending web 10 is secured within the upper portion of each support and the upper edge of each web is provided with a slot 11 for a purpose to be hereinafter set forth.

A base plate 12, as shown in Fig. 5, is positioned upon the top of each end support, 70 and transverse movement of the plate upon the tie is prevented by extending their transverse ends 13 at right angles for engagement with the transverse ends of the support. Two pairs of upwardly extending oppositely disposed lugs 14 are provided by cutting transversely of the plate at spaced intervals and by bending up the portions defined by the cuts. These upstanding lugs 14 are adapted to extend through the slots 15 provided in 80 the edges of the side flange 16 of the rails 17. Due to this construction, the transverse movement of the rails upon their respective base plate 12 is prevented.

A bar 18 extends longitudinally of the 85 cross tie through the slots 11 of the webs 10, and is movable longitudinally therethrough for a purpose which will presently appear. The plate 19 is secured to the top of one end of the bar 18, as clearly shown in Fig. 3, 90 and extends longitudinally of the bar and transversely beneath the top of one of the end supports 8. At the point where this plate reaches the end of the bar 18, it is extended upwardly a substantial distance as 95 at 20, then inclined inwardly of the bar as at 21 whereby the terminal of portion 21 engages at the juncture of the rail web and the tread portion of the rail. Consequently, the upstanding portion 20 of this plate engages 100 with a portion of the longitudinal edges of both the base plate 12 and the outside flange 15 of the rail. As shown in Figs. 1, 2 and 4, the edges of the portion 21 diverge upwardly to the rail and provide a broad engaging edge therefor. To brace the inner longitudinal edges of the face plate 12 and the rail flange 15, a sleeve 22 is slidably mounted upon the bar 18. This sleeve is equipped with a rail engaging member 23, 110 and its construction and function is identical with the portions 21 and 20 of the plate 19.

The upstanding portion 24 of the rail engaging member 23 engages with the relative inner longitudinal edges of the base plate and the inner rail flange while the terminal of 5 this member engages the rail at the juncture of its tread portion and web. The sleeve 22 is retained in such position whereby its rail engaging member 23 is in the proper position, by means of a wedge shaped key 25 extending 10 through a slot 26 provided in the movable bar 18.

The other rails are retained upon the opposite end of the tie the same as its co-acting rails, with the exception that instead of a 15 plate 19 being secured to the opposite end of the bar 18, a sleeve 27 is slidably mounted upon the bar whereby its portion 21 engages with the relative outside of the rails. This sleeve 27 is retained in such position that 20 its rail engaging member 21^a engages with the edges of the base plate and rail flange by the shackle of a padlock 29 abutting against the end of the sleeve and extending through an opening in the bar 18.

25 Consequently, when it is desired to remove the rails from the tie, the shackle of the padlock is removed from its opening in the bar 18 so that sleeve 27 may be moved upon the bar 18 outwardly of the rail. The key 25, adjacent the plate 19 is removed at which time the bar 18 may be moved longitudinally of the cross tie to disengage the rail engaging portion 21 of the plate 19 outwardly from the rail 17. The key 25 of 30 the sleeve 22 mounted upon the opposite end of the bar 18, may be securely locked in position, and it is not necessary to remove this key unless it is desired to entirely remove the bar 18 from the cross tie. After the 35 desired adjustment has been accomplished, the bar 18 may be moved longitudinally of the cross tie to its normal position whereby the rail engaging members of the sleeves and plates 19 are in their proper position, 40 and the shackle of the padlock 29 and keys 25 inserted in their respective openings in the bar 18, to securely lock the same and its associated parts in position.

Having thus fully described my invention what is claimed is:

50 1. In a cross tie, a bar extending longitudinally of the tie, a plate on each end thereof, rails supported upon said plates,

means for preventing longitudinal movement of the rails upon the tie, and means 55 carried by said bar for preventing transverse movement of the rails upon the tie.

2. In a cross tie, supports carried thereby, a movable bar extending longitudinally of the tie and transversely through said supports, a plate on each support, rails mounted upon said plates means for preventing longitudinal movement of said rails placed upon said support, and rail engaging members carried by said bar and engaging the 60 longitudinal edges of said rail flanges and plates for preventing transverse movement of the rails upon the support.

3. In a cross tie, supports carried thereby, a movable bar extending longitudinally of 70 the tie and transversely through said supports, a plate on each support, rails mounted upon said plates, means for preventing longitudinal movement of said rails and placed upon said supports movable sleeves on said 75 bar, a rail engaging member secured to each sleeve and engaging the longitudinal edges of said rails and plates, a plate secured to the top of said bar adjacent the end thereof beneath a co-acting sleeve, the end of said 80 plate being extended to engage a rail and the longitudinal edges of said rails and plates to prevent transverse movement of said rails and said first named plates upon the support.

4. In a cross tie, a base plate on each end of said tie, rails mounted upon said plates, means for preventing longitudinal movement of said rails placed upon said tie, a bar extending longitudinally of the tie, 90 means thereon for preventing transverse movement of said base plates and rails upon said tie, and a rail engaging member rigidly secured to said bar to engage the rails and the longitudinal edges of said rail flanges 95 and plates to prevent transverse movement of said rails and first named plates upon the tie.

In testimony that I claim the foregoing as my own, I have hereto affixed my signature in the presence of two witnesses.

RIMMON J. CARR.
